UNITED STATES PATENT OFFICE.

OLOF QUIST, OF SAN DIEGO, CALIFORNIA.

APPLIANCE FOR OIL PRESERVATION OF PILING IN WATER.

978,643.

Specification of Letters Patent. Patented Dec. 13, 1910.

Application filed October 28, 1908. Serial No. 459,925.

To all whom it may concern:

Be it known that I, OLOF QUIST, citizen of the United States, residing at San Diego, in the county of San Diego and State of California, have invented certain new and useful Improvements in Appliances for Oil Preservation of Piling in Water; and I do hereby declare the following to be a full, clear, and exact description of the invention, such as will enable others skilled in the art to which it appertains to make and use the same.

My invention relates to appliances for preserving piling, telegraph and telephone poles or the supporting timbers of any structure when said supports come in contact with the water or moisture from the earth.

I employ oil as the preservative and this invention has to do with the means used for holding the oil around the piling or other supports at the desired place which is just above the water.

Among the objects I have in view are to protect the supports from insects and fire as well as the decay which results from contact with the air alone.

Another object is to support the tube for holding the oil around the piling rigidly in place thereon at the desired level.

A further object is to provide for the automatic shifting of the oil up and down on the piling to accord with the rising and falling of the tide, whereby the preserving fluid always protects the vital part of the piling, namely, that just above the water line.

Still another object is to protect the piling and the oil-containing casings from floating debris in swift running streams.

Further objects will become apparent from the following description.

The invention consists in the features of construction and combinations of parts hereinafter described and specified in the claims.

In the accompanying drawings: Figure 1 is a perspective view showing two piles supporting a platform and equipped with protectors constructed in accordance with my invention, one of said protectors or tubular casings being partially broken away and its cover shown raised therefrom to better illustrate its construction. Fig. 2 is a detailed view of one member or side plate compris-

ing one of the protectors or casings. Fig. 3 is an elevation of the piles and platform, illustrating a modified form of protector in section, and Fig. 4 is a horizontal section taken through the lugs on the protectors to which the braces are connected.

While I have illustrated my protectors as applied to piling, it should be understood that they may be used with equal success in other supports. Nor do I limit myself to the details of construction herein shown and described but reserve the right to make such changes as fairly fall within the scope of the appended claims.

Referring more particularly to the drawings, A designates the piles which support the timbers B of the platform.

C are the protectors or tubular casings which hold the oil. These protectors are illustrated in Fig. 1 as having oppositely extending ribs C¹ at their edges which are presented to the current and are designed to protect the piling as well as the casing from being crushed or otherwise injured by floating debris. In calm waters, the protectors or casings may be round in cross-section, as shown in Figs. 3 and 4.

The protector illustrated in Fig. 1 is composed of two similar side plates C¹ which are secured together at their edges by bolts 85 passed through holes C², Fig. 2. Said plates are further secured by clamps D, one of which is preferably attached to the middle of each casing and connected to the platform by adjustable rods or braces E made in sections E' coupled by turn buckles E² whereby said casings are held securely in the desired positions. An additional protection is afforded the casing against floating debris by the skeleton shield D¹ which extends along the 90 ribs of the protector facing upstream. The casings are clamped rigidly to their piles by means of sectional tapered blocks G connected to the cover plate H by vertical rods F. Said cover plate may be provided with 100 an opening H¹ having a pivoted closure I, as illustrated in Fig. 1, for pouring in the oil. Said blocks are wedged into the lower end of each casing by tightening the nuts F¹ upon the cover plate which is pressed tightly 105 down on the top of the casing by the same operation thereby excluding insects, fire and air. The bottoms of the casings or protectors do not have to be sealed by the blocks G because the water will support the oil on 110

its surface in said casings. The variation in the surface line of the oil due to the shifting of the tide is illustrated at *a—a* while the variation in the tide line is shown at *b—d*.

5 Fig. 3 illustrates how the casings may be extended down to rest upon the bottom of the river or pond. In such case, the clamping blocks may be omitted. The cover plates may also be dispensed with, as here, when 10 insects are not prevalent. It will be observed that the modification as well as the preferred form of protector allows the oil to shift from the lowest to the highest water line so that it always covers the part of the piling in need 15 of protection. It may be noted that any chemical preservative may be employed in place of oil.

I claim:—

- 20 1. The combination, with supports of the character described, and a superstructure, of tubular casings around said supports, and means of connection between said casings and superstructure.
- 25 2. The combination, with supports of the character described, and a superstructure, of tubular casings around said supports, and adjustable means of connection between said casings and superstructure.
- 30 3. The combination, with a support of the character described, of a tubular casing extending well above the water line and partially open at its bottom, a closure at the top

of said casing and a preservative fluid on the surface of the water within said casing whereby said fluid is capable of shifting 35 with the tide.

4. The combination, with a support of the character described, of a tubular casing around said support, and tapered blocks clamped between said support and casing for 40 the purpose specified.

5. The combination, with a support of the character described, of a tubular casing around said support, a cover plate for said casing, tapered blocks in the lower end of 45 said casing, and rods connecting said cover plate and blocks for the purposes specified.

6. The combination, with a support of the character described, of a tubular casing around said support and having a projecting 50 rib at its side facing upstream for the purpose specified.

7. The combination, with a support of the character described, of a tubular casing around said support and having a projecting 55 rib at its side facing upstream, and a skeleton shield arranged along and conforming to said rib.

In testimony whereof, I affix my signature, in presence of two witnesses.

OLOF QUIST.
